GRAVITY FEED FUEL CONTROL MEANS FOR
WICK TYPE BURNERS

Averd Nelson, Wisconsin Rapids, Wis., assignor to
Prentiss Wabers Products Co., Wisconsin
Rapids, Wis., a corporation of Wisconsin

Application January 15, 1947, Serial No. 722,116

7 Claims. (Cl. 158—36.6)

1

The present invention relates to improvements in controls for burners.

More particularly, the present invention relates to improvements for controlling the flow of liquid fuel to a burner, an example of which is a kerosene burner.

An object of the present invention is to provide an improved control which may be applied to a wick holder and burner of conventional design and which will have improved simplification over prior devices.

A further object is to provide a control for a burner which avoids the difficulties which have previously been encountered in the ordinary needle valve control.

A further object is to provide an improved control for a liquid fuel burner which avoids difficulties heretofore encountered due to leaks in the fuel line.

A further object is to provide an improved control for a liquid fuel burner which will result in even burning at low flame.

A further object is to provide a control for a burner which is not likely to wear and which requires only a minimum of maintenance to keep it in operating condition.

A further object is to provide a control for a liquid fuel burner which is simple, sturdy in construction and not likely to get out of order.

A further object is to provide a control which is efficient and compact.

A further object is to provide a control for a liquid fuel burner which is cheap to manufacture and efficient in operation.

A further object is to provide a control for an oil burner well adapted to meet the needs of ordinary service.

Further objects will appear as the description proceeds.

Referring to the drawings.

Figure 1 is a view in side elevation illustrating one embodiment of the present invention;

Figure 2 is an end view of the construction illustrated in Figure 1, Figure 2 being taken in the direction of the arrows 2—2 in Figure 1;

Figures 3 and 4 illustrate details of construction of the device illustrated in the preceding figures;

Figure 5 is a top plan view of a modified construction;

Figure 6 is a side view of the construction illustrated in Figure 5, Figure 6 being taken in the direction of the arrows 6—6 of Figure 5;

Figure 7 is a fragmentary view illustrating an end view of the construction shown in Figure 6.

2

Figure 7 being taken in the direction of the arrows 7—7 in Figure 6;

Figure 8 illustrates a detail of construction;

Figures 9 and 10 are views in side elevation and top plan, respectively, illustrating another modification; and

Figures 11, 12 and 13 are views in top plan, end elevation and side elevation, respectively, of a construction embodying a gang of burners with control means therefor embodying the principles of the present invention.

Referring first to the embodiment of the invention illustrated in Figures 1, 2, 3, and 4, the numeral 10 indicates a framework for supporting a burner and the control therefor. The burner is indicated by the numeral 11 and may consist of a wick holder 12 and a flame distributor 12a which may be of conventional design. Said wick holder 12 is mounted upon and communicates with the interior of a tube or stringer 13, being welded thereto, for example, as indicated by the numerals 14—14.

Said tube or stringer 13 is adapted to have a swinging movement in a vertical plane, i. e. in the plane of the paper as the parts are illustrated in Figure 1. To allow this swinging movement while connected to a stationary fuel supply, the stringer 13 is connected to a bellows 15, the other extremity of which is secured to a fitting 16, threaded into an opening in the transversely extending fuel supply pipe 17. Secured to the pipe or stringer 13, adjacent to the bellows 15, is a bracket 18. Said bracket includes a split sleeve portion 19 encircling the tube or stringer 13 which sleeve portion has upstanding flanges 20—20, having apertures provided with a bolt 21 and a nut 22 whereby the sleeve portion 19 may be secured in tight gripping relationship with the tube or stringer 13. Said bracket 18 is provided with the flaring arms 23—23 engaging brackets 24—24 secured to the supply pipe 17. Said brackets may be united by means of struts, one of which is indicated by the numeral 24a.

The axis of swing of the tube or stringer 13, with respect to the brackets 24—24, is indicated by the center line 25 which is disposed in intersecting relationship with the bellows 15 or adjacent thereto.

The supply pipe 17 and fitting 16 are rigidly carried by the frame 10. The supply pipe 17 supports a sump 26 which may be supplied by the fuel tank 27. The sump 26 and fuel tank 27 may be of the well known barometric control type whereby a predetermined liquid level, indicated

by the reference character 26a, will be maintained in the sump 26.

The tilting or swinging of the tube or stringer 13 with its burner 11 about the axis 25 is controlled by a handle 28 located at the extremity of a shaft 29 having an offset crank portion 30 adapted to operate in a slot 31 in a bracket 32 fast with the tube or stringer 13. Said handle 28 has a portion 33 hereof bent in right angular relationship with the shaft 29. A spring 34 is disposed in encircling relationship with the shaft 29 and engages a cotter pin 34a or the like. Said spring urges the portion 33 of the handle 28 into engagement with an embossed portion 35 fast with frame 10. Said embossed portion 35 is provided with a plurality of spaced indentations 36-36 whereby, due to the bias of the spring 34, the handle 28 may be held releaseably in any one of a plurality of spaced positions.

Swinging of the handle 28 through an arc will communicate a lifting or lowering movement to the bracket 32, swinging the tube or stringer 13 about the axis 25. By reference to Figure 1, it will be noted that when said tube or stringer is in its uppermost position, the wick holder 12 will be located above the fuel level 26a in the sump 26 so that said wick holder will not be supplied with fuel. As the handle 28 is swung in the direction to lower the adjacent extremity of the tube or stringer 13, the wick holder will be lowered to and below the liquid fuel level 26a, the maximum depth of fuel being had when the stringer 13 is in its lowermost position as indicated in dotted lines in Figure 1.

Communication between the interior of the tube or stringer 13 and the burner 11 is had through the aperture 37 located at the bottom of said burner. It is important that this aperture be located at the high side of the burner 11 considering conditions when said burner is in its off position (its uppermost position). In other language, the aperture 37 is located at that portion of the burner 11 distant from the axis of swing on the tube or stringer 13 and disposed symmetrically with the plane of swing of said burner. According to the illustrated embodiment of the present invention, only one aperture 37 is provided. If apertures providing communication between the tube or stringer 13 and the burner 11 were provided on the low side of said burner (considering conditions when said burner is in its uppermost position) an uneven flame would result on low fire for the reason that the fuel would tend to run out of the lower part of the burner and that remaining in the burner would burn on only one side of the wick. According to the illustrated embodiment of the present invention, the burner will function evenly at low flame for the reason that the liquid fuel, inasmuch as it must pass through the aperture 37 on the high side of the burner (when the burner is adjacent to its uppermost position) will saturate the wick in the burner and will continue to pass around to the low side of the burner wick, making possible a more even saturation of the wick at periods of low fire as well as at other periods of fire.

Two pins 36a-36a extending from the embossed portion 35 definitely limit swinging movement of the handle 28, which swinging movement will approximate 180 degrees. Said pins 36a-36a will definitely limit the extent to which the bellows 15 may be bent. As an added safety feature to protect the bellows, the bracket 24-24 and the flaring arms 23-23 of the bracket 18 have co-operating portions to limit the swinging of the tube or stringer 13. This construction is illus-

trated in Figure 4 from which it will be noted that the bracket 24 is provided with the upper and lower flanges 38-38 which co-operate with a squared portion 39 of the swinging bracket 18 to limit swinging movement of said bracket 18, thereby protecting the bellows 15 against excessive bending. In other words, the corners of the squared portion 39 of the swinging bracket 18 engage alternatively the upper and lower flanges 38-38 of the stationary bracket 24, and therefore limit the swinging movement of the bracket 18 and of the tube or stringer 13. As a manufacturing detail, the brackets 24-24 may profitably be made in one piece, being connected by struts 24a-24a as above described and illustrated, so that the distance between said brackets will be accurately determined as, for example, by swaging in a die, resulting in a relatively cheap and accurate construction.

As a further safety feature, the floor 40 of the frame 10 is located in a position to support bracket 32 when said bracket is in its lowermost position; that is in the position in which the burner 11 is located for high flame. Therefore in the event of failure of the handle construction 28 with its associated spring 34, the burner 11 would be prevented from moving below a predetermined high flame position both by the co-operation of the portion 39 of the bracket 18 with the flanges 38 of the brackets 34 but also by contact of the bracket 32 with the floor 40.

Referring now to the embodiment of the present invention illustrated in Figures 5, 6, 7 and 8, a construction is illustrated in which the sump 41, carrying a fuel tank 42, is swingingly supported on a pair of brackets, one of which is illustrated in Figure 6 and indicated by the numeral 42a. Said brackets 42a-42a are rigidly mounted upon the frame 43. Rigidly secured to the sump 41 is the tube or stringer 44, said tube or stringer having an aperture 45 for communication with the interior of said sump. As illustrated in Figure 6, the aperture 45 in the tube or stringer 44 has communication with the nipple 46 which nipple is united with the tube or stringer 44 by welding or the like. The outer wall of the nipple 46 is provided with a groove for the reception of a collar 47, the wall of which is of U-shaped cross section. The lower portion of the sump 41 is provided with a depressed portion 48, the lower extremity of which is provided with an apertured flange 48a fitting within the collar 47. Said parts may be assembled and swaged together in a manner which will be obvious without detailed explanation whereby to provide a tight joint between the sump 41 and the tube or stringer 44.

A burner 49 is connected to the tube or stringer 44 adjacent to the right-hand extremity of said tube or stringer as the parts are viewed in Figures 5 and 6. Said tube or stringer 44 and burner 49 are adapted to be raised and lowered with a swinging movement about the axis 50 which is the axis of swing of the sump 41 and tank 42 in the brackets 42a-42a. The raising and lowering of the burner 49 is controlled by the handle 51 connected to the shank 52, provided with the offset crank portion 53. Said crank portion 53 is positioned within a slot 54 in a bracket 55 secured to the tube or stringer 44 adjacent to the swinging extremity thereof. Said bracket 55, as illustrated in Figure 7, encircles the tube or stringer 44 at least partially and is secured thereto by welding, brazing or the like. Shaft 52 is journaled in a pair of brackets 56 and 57 secured to the frame 43 of the stove or the like of which

5

the burner 49 forms a part. A spring 59 disposed in encircling relationship with the shaft 52 reacts against a cotter pin 52a extending through said shaft and urges the shaft toward the right as the parts are viewed in Figure 7. The shaft 52 is provided with a handle 51 which includes a reversely bent portion 60 extending toward the shaft 52 and this reversely bent portion 60 is adapted to be releasably held within any of the notches 61-61 formed in the embossed portion 61a of the bracket 51, fast with the frame 43.

Communication between the interior of the tube or stringer 44 and the burner 49 is had through the aperture 62, which, as explained above in connection with the aperture 37 (Figure 1) should be located at the high side of its corresponding burner, considering conditions when said burner is in its uppermost position. That is, the aperture 62 is located at that portion of the burner 49 distant from the axis of swing of tube or stringer 44 and is positioned symmetrically with the plane of swing of said burner.

The frame 43 of the stove is provided with the upstanding wall 63 which wall is recessed to receive the tube or stringer 44 whereby to limit the downward movement of the burner 49.

The mode of operation of the embodiment of the present invention illustrated in Figures 5 to 8 inclusive will be clear from the description of the embodiment of the invention illustrated in Figures 1 to 4. According to Figures 5 to 8, the handle 51 may be swung through an arc approximating 180 degrees. At one extreme position of said handle the burner 49 will be in its uppermost position in which any liquid fuel in the bottom of said burner will drain back through the tube or stringer 44 toward the sump 41. At the other extreme position of the handle 51 the burner 49 will be in its lowermost position wherein liquid fuel will flow by gravity from the sump 41 through the tube or stringer 44 to the bottom of the burner 49 providing maximum flame. The intermediate flames may be had by choosing intermediate positions of the handle 51. In the event of failure of the spring 59, downward movement of the burner 49 will be limited by reason of engagement of the tube or stringer 44 with the bottom of the recess in the wall 63.

Referring now to the embodiment of the invention illustrated in Figures 9 and 10, a relatively stationary sump 64 is provided having mounted thereon the tank 65. Communicating with the bottom of the sump 64 is the pipe 66 which has connected thereto a packing gland 67 which takes the form of an elbow, one arm of which, indicated by the numeral 68, communicates with the interior of the pipe 66. The other arm of said packing gland, indicated by the numeral 69, provides means for rotatably receiving the end portion 70 of the pipe or stringer 71 which leads to a burner 72. The pipe or stringer 71 is turned at right angles intermediate of its length as clearly illustrated in Figure 10 whereby the end portion 70 thereof may lie in parallel relationship with the pipe 66 while the other end portion 70a of said pipe or stringer is being swung vertically in a plane at right angles to the pipe 66. The aperture 70b, providing communication between the pipe or stringer 70a and the burner 72, is located on the high side of said burner considering conditions when said burner is in its uppermost position. That is, said aperture is located at that portion of the burner distant from the axis of swing thereof and is disposed symmetri-

6

cally with the plane of swing burner of said burner.

It will not be necessary to describe the packing gland 67 in detail, it being sufficient to state that said packing gland receives the end portion 70 of the pipe or stringer 71, packing material indicated by the numeral 73 being disposed exteriorly of said end portion 70 and interiorly of the arm 69 of the packing gland 67. A bushing 74 may be provided for engaging and compressing the packing material 73, said bushing 74 being engaged by the cap member 75 which is threaded interiorly to engage the threaded extremity of the arm 69.

It will be understood without further explanation that the packing gland 67 will provide a liquid tight flexible connection between the pipe 66 and the pipe or stringer 71 while permitting said pipe or stringer 71 to have a swinging movement about an axis parallel with the axis of the pipe 66.

The sump 64 and the tank 65 will have barometric control means similar to the corresponding instrumentalities illustrated and described in connection with the preceding figures, said control means maintaining a predetermined oil level in the sump 64 which oil level is indicated by the numeral 75a in Figure 9.

Similarly to the embodiments of the invention illustrated in the preceding figures, the raising and lowering of the burner 72 will control the feeding of oil from the sump 64 to said burner. When said burner is in its lowermost position as indicated in full lines in Figure 9, said burner will be positioned for high flame. When said burner is raised to its uppermost position as indicated in dotted lines in Figure 9, the wick portion of said burner will be raised above the liquid level 75a, stopping the feeding of oil. Any intermediate position between the uppermost and lowermost positions of the burner may be chosen and maintained by any preferred adjusting means.

Figures 11, 12 and 13 illustrate a construction in which a gang of burners may be controlled according to the present invention with one movement of the adjusting means.

Referring to the structure illustrated in Figures 11, 12 and 13, a tank 76 is provided fixedly mounted upon a bracket 77 fast with the frame, not illustrated, of the stove. Pivotally connected to said bracket 77 is a sump assembly indicated as a whole by the numeral 78. As illustrated, said sump assembly is made up of three sumps 79, 80 and 81 fixed relative to each other but swingable as a whole about the axis 82. The tank 76 is provided with three nipples 83-83, each of which projects down into its own individual sump. Each of said nipples is provided with a valve 84 by means of which a predetermined oil level may be maintained in each of the sumps 79, 80 and 81. Each of said sumps 79, 80 and 81 communicates with a pipe or stringer 85, each leading to its individual burner 86. The elevation of the burners 86-86 may be controlled by the rotatable shaft 87 carried by the brackets 88-88 and by the embossed member 89 being fixed relative to the stove. Said shaft 87 is provided with a plurality of crank portions, which need not be illustrated or described in detail, co-operating with slots 90-90 in the brackets 91-91 fixed relative to the swinging extremities of the pipes or stringers 85-85.

The shaft 87 may be provided with a cotter pin 92 and between said cotter pin 92 and the embossed member 89 a spring may be disposed in

encircling relationship with the adjacent portion of the shaft 89 whereby said shaft 87 will be urged toward the left as the parts are viewed in Figure 11. The right hand extremity of the shaft 87 as the parts are viewed in Figure 11 is provided with the handle 93 having an end portion 94 turned into right angular relationship with the axis of the shaft 87. The embossed member 89 is provided with an arcuate rib 95 having a plurality of indentations 96-96 for receiving the end portion 94 of the handle 93. The aperture 97, providing communication between each pipe or stringer 85 and its corresponding burner 86 is located at the high side of said burner, considering conditions when said burner is in its uppermost position. That is, said aperture is located at a region of said burner spaced from the axis of swing of said burner and symmetrically disposed with respect to the plane of swing of said burner.

It will be clear that the gang of burners 86-86 may be moved to and held at a plurality of selectable positions with respect to the oil level in the sumps 79, 80 and 81. It is a matter of choice whether the oil level in each of the sumps 79, 80 and 81 will be the same or whether the oil level in one or more of said sumps may vary from the level in the remainder of the sumps. In other words, it is a matter of choice whether the operator in raising and lowering the gang of burners 86-86 will control the flowing of oil equally to all three burners or whether the parts will be so designed that the flow of oil to one or more of the burners will vary from the flow of oil to the remainder of the burners.

The present invention has the advantage that the parts may be made of substantial construction at a relatively low cost. It presents very little likelihood of getting out of order. The control operates efficiently and evenly at low fire as well as at higher fires. The present invention has the further advantage that it makes possible an efficient liquid fuel burner of minimum overall height, a construction which is very important in the kerosene stove field.

Though certain preferred embodiments of the present invention have been described in detail, many modifications will occur to those skilled in the art. It is intended to cover all such modifications that fall within the scope of the appended claims.

What is claimed is:

1. In combination, a relatively stationary supply vessel, means for maintaining a predetermined liquid level within said vessel, a tube, flexible connecting means connecting said tube to said supply vessel, a burner communicating with said tube and means for tilting said tube and said burner as a unit about an axis extending through said connecting means with a movement in a vertical plane to change the relative elevations of said burner and said liquid level in said supply vessel whereby liquid will flow from said burner toward said supply vessel or will flow from said supply vessel toward said burner through said tube in response to changes in said relative elevations, the only communication between said burner and said tube being at the bottom of said burner on the high side of said burner when said burner is in its elevated position and being located symmetrically with said plane.

2. In combination, a relatively stationary supply vessel, means for maintaining a predetermined liquid level within said vessel, a tube, flexible connecting means connecting said tube to

said supply vessel, a burner communicating with said tube and means for tilting said tube and said burner as a unit about an axis extending through said connecting means with a movement in a vertical plane to change the relative elevations of said burner and said liquid level in said supply vessel whereby liquid will flow from said burner toward said supply vessel or will flow from said supply vessel toward said burner through said tube in response to changes in said relative elevations, the only communication between said burner and said tube being at the bottom of said burner on the high side of said burner when said burner is in its elevated position and being located symmetrically with said plane, and means for re-

leasably holding said elevation changing means in a plurality of positions intermediate of the range of positions of said supply vessel and said burner.

5 10 15 20 25 30 35 40 45 50 55 60 65 70 75

3. In combination, a relatively stationary supply vessel for liquid fuel, means for maintaining a predetermined liquid level in said vessel, a burner and tube means connecting said burner with said vessel, means for tilting said tube means and said burner as a unit with a movement in a vertical plane between positions wherein fuel will flow from said vessel toward the bottom of said burner and wherein fuel will flow from the bottom of said burner toward said vessel and flexible connecting means connecting said tube and said vessel whereby said tube may be tilted without moving said vessel, the only communication between said burner and said tube being at the bottom of said burner on the high side of said burner when said burner is in its elevated position and being located symmetrically with said plane.

4. In combination, a relatively stationary supply vessel for liquid fuel, means for maintaining a predetermined liquid level in said vessel, a burner and tube means connecting said burner with said vessel, means for tilting said tube means and said burner as a unit with a movement in a vertical plane between positions wherein fuel will flow from said vessel toward the bottom of said burner and wherein fuel will flow from the bottom of said burner toward said vessel and flexible connecting means connecting said tube and said vessel whereby said tube may be tilted without moving said vessel, said flexible connecting means embodying a bellows, the only communication between said burner and said tube being at the bottom of said burner on the high side of said burner when said burner is in its elevated position and being located symmetrically with said plane.

5. In combination, a relatively stationary supply vessel for liquid fuel, means for maintaining a predetermined liquid level in said vessel, a burner and tube means connecting said burner with said vessel, means for tilting said tube means and said burner between positions wherein fuel will flow from said vessel toward the bottom of said burner and wherein fuel will flow from the bottom of said burner toward said vessel and flexible connecting means connecting said tube and said vessel whereby said tube may be tilted without moving said vessel, said flexible connecting means embodying a packing gland, the only communication between said burner and said tube being at the bottom of said burner on the high side of said burner when said burner is in its elevated position and being located symmetrically with the plane of tilt of said tube.

6. In combination, a tube, means for tiltably

raising and lowering said tube progressively about an axis with a movement in a vertical plane, a liquid fuel supply member connected to deliver fuel to and receive fuel from one end of said tube, said liquid fuel supply member being fixed in location relative to said axis, a burner communicating with the other end of said tube and tiltable as a unit with said tube, and means for selectively changing the elevation of said burner with respect to said fuel supply member whereby fuel may flow from said burner toward said supply member or may flow from said supply member toward said burner through said tube in response to the position of said burner, flexible connecting means for delivering fuel from said fuel supply member to said tube, said axis extending through said flexible connecting means, the only communication between said burner and said tube being at the bottom of said burner on the high side of said burner when said burner is in its elevated position and being located symmetrically with said plane.

7. In combination, a tube, means for tiltably raising and lowering said tube progressively about an axis with a movement in a vertical plane, a liquid fuel supply member connected to deliver fuel to and receive fuel from one end of said tube, said liquid fuel supply member being fixed in location relative to said axis, a burner communicating with the other end of said tube and tiltable as a unit with said tube, and means for selectively changing the elevation of said burner

with respect to said fuel supply member whereby fuel may flow from said burner toward said supply member or may flow from said supply member toward said burner through said tube in response to the position of said burner, flexible connecting means for delivering fuel from said fuel supply member to said tube, said axis extending through said flexible connecting means, the only communication between said burner and said tube being at the bottom of said burner on the high side of said burner when said burner is in its elevated position and being located symmetrically with said plane, and means for releasably holding said elevation changing means 15 in a plurality of positions intermediate of the range of positions of said burner.
